UNITED STATES PATENT OFFICE

JOSEPH D. ZAHM, OF LITITZ, PENNSYLVANIA, ASSIGNOR TO ANIMAL TRAP COMPANY OF AMERICA, OF LITITZ, PENNSYLVANIA, A CORPORATION OF PENNSYLVANIA

APPARATUS FOR BLANKING AND FORMING JAWS FOR STEEL TRAPS

Application filed May 24, 1929. Serial No. 365,655.

This invention relates to a mechanism for the formation of blanks such as strips, bars and the like by the cutting thereof from raw material and the subsequent shaping of the same according to requirements.

It is the main object of the invention to provide an improved machine of the above character which will be wholly automatic in its operation.

More specifically it is an object of the invention to provide a machine adapted to produce curved, bowed or similarly shaped jaw members from sheet material.

A further object of the invention is to provide a machine having a cutting mechanism and a forming or shaping mechanism with feeding means for feeding the cut blanks to the forming mechanism.

Other objects and features of the invention will be apparent from the following description taken in conjunction with the accompanying drawings, the invention being particularly indicated in the appended claims.

25 In the drawings:—

Fig. 1 is a front view of one machine embodying this invention;

Fig. 2 is a side view of the machine;

Fig. 3 is an enlarged front view of one portion of the machine with parts removed for the sake of clearness;

Fig. 4 is an enlarged side view of the part of the machine shown in Fig. 3 also with parts removed;

Fig. 5 is a plan view of portions of the mechanism; and

Fig. 6 is a side elevation of a further detailed portion of the mechanism.

In the actual specific construction illustrated in the drawings which forms one convenient embodiment of the invention as applied to the formation of jaw members for animal traps, there is provided a ram 1 movable vertically in the press frame under the action of a connecting rod 2 on a camshaft 4. The ram carries at its lower end a punch 6 which cooperates with die 7 located in the bed of the machine 8. In front of the machine and at a lower level than the die, is located a jaw-forming member 10 which may

be of any desired shape, according to the actual configuration it is required to give to the blank member. On the camshaft 4 is also an eccentric or cam 5 connected by means of an adjustable member 9 to a crosshead 45 carrying slide rods 3 movable in upper and lower guide members respectively on the main frame 50, 51. The slide rods carry at their lower ends finger members 11 and 12 movable in slots 13 and 14 and provided with springs, 46, 47 whose function will be indicated hereafter. The inner ends of these extensions or fingers 11, 12 are so positioned that when the crosshead moves vertically downwards they travel close to the sides of the jaw-forming member 10, as will be gathered from Fig. 1.

On either side of the jaw-forming member 10 and in front of the machine are supporting members 15 and 16 pivoted at points 17 and 18 and controlled by springs 19 and 20.

A clamping member 21 movable under the combined control of a spring member 22 is mounted on a lever 23 pivoted to die block 7 and its upper end moves in a cam groove 24, cut in a convenient portion of the ram. A spring 25 is also provided and attached to a part of the machine to ensure positive control over the lever 23. At the rear of the machine and mounted upon a common fulcrum pin 26, are three lever members 27, 28 and 29, movable about the pin 26 under the control of an upper arm or lever member 30 attached to the central member 28 and rotatable with the same. The arm or lever 30 is so positioned that it lies in the path of travel of a cam member 31 mounted upon the ram which is provided with a suitably shaped slot into which the cam 30 projects at the appropriate times.

Beneath the blanking die 7 and in register therewith is a vertical slot 34 which communicates with the horizontal slot 33 beneath the die, cut blanks thus falling down slot 34 into slot 33. In the slot 33 is located a slidable placing plate 35 and the movement of the same is such that it will move blanks which fall down the slot 34 out to the front of the machine where the slot 33 terminates adjacent to the forming member 10. Placing

100

plate 35 as shown in Fig. 5 is attached by lugs 36 through which passes a pin 37 extending through slots 38 (Fig. 4) in the cam members 27 and 29.

5 Located beneath the slot 33 and on either side of the jaw forming member 10 are two holes 40 and 41 in which are movable kicker-rods 42 (Fig. 3) (Figs. 5 and 6). As shown in Fig. 4 and Fig. 6 the kicker-rods are associated with spring members 44 and as shown in Fig. 5 and Fig. 6 have a pin 43 carrying a roller 48 which contacts with the forward face of the middle cam 28.

In operation the ram is actuated by means of the camshaft 4 and the connecting rod 2 and oscillates vertically, cutting at each descent a blank from a sheet of material placed over the die and the blanks so-cut fall down the slot 34 into the forwardly extending slot 33. Upon the upward movement of the ram the upper end of lever 30 riding in the slot in the cam 31 is moved upwardly and backwardly and the cam levers 27, 28 and 29 are moved forwardly so that the placing plate 35 contacts with the lowermost blank and moves it forward; this taking place when the slot 34 is filled with blanks and the placing plate is fixed in the machine.

Upon the next downward movement of the ram the blanks located on the jaw-forming member 10 is held by means of the clamp 21 (Figure 1) actuated through the cam slot 24 and the arm 23, and when so held at its center further rotation of the shaft causes movement downwards of the crosshead 45 and the extensions or fingers 11 and 12 thereon contact with and press down the ends of the blank projecting over the sides of the jaw-forming member 10 and the blank is thus shaped to the configuration of the jaw-former 10.

The supporting members 15 and 16 during this operation rotate about their pivots 17 and 18 under pressure from the fingers 11 and 12 and thus allow the ends of the blank to be folded round the former. On the return movement of the crosshead and the ram the fingers are raised and are held against the slide rods 3 by springs 46 and 47, and supporting members 15 and 16 resume their horizontal position under the control of springs 19 and 20, and the clamp 21 is released by the lever 23. Upward movement of the ram will also cause a further blank to be pushed forward by the plate 35 and just prior to this the kicker-rods 40 and 41 are moved forward against their associated springs by the levers 27 and 29 to remove the blank just previously formed from the jaw-forming member 10, so that the next unshaped blank can be positioned on top of the former.

On continued rotation of the shaft 4 the blanks are fed forward by the placing plate, their ends resting upon the inner ends of the

spring controlled members 15 and 16, the fingers 11 and 12 are brought down by the crosshead to bend the blank round the former 10 and just prior to the contact of the finger with the blank the clamp 21 descends to hold the center part thereof firmly on the forming member 10.

The sheet material may be fed to the machine in sheets of a definite size automatically or manually or may on the other hand be arranged as a roll and fed automatically to the machine by the unrolling of the same.

It will be seen, from the above, that there is provided a machine in which blanks are cut and when so cut are fed forward automatically to a shaping or forming device and are there automatically bent to the required shape and when so bent and shaped are ejected in the finished condition. It will be seen, furthermore, that the whole cycle of operations is purely automatic and that the machine requires little or no attention, whilst at the same time it is of simple and efficient construction.

While the invention has been described in detail with respect to one specific embodiment for the formation of jaw members for animal traps it is to be understood that this is simply a convenient construction for illustrative purposes and the invention is capable of use in machines for the formation of any curved or otherwise shaped body such as a handle, lever or the like and is capable of many and various modifications. The invention, therefore, is not to be taken as limited to the embodiment shown but as being particularly defined in the appended claims.

What I claim is:—

1. A blank-forming machine comprising a movable member, a punch member and finger members thereon, a cutting die operatively associated with said punch member and means for feeding a blank from said cutting die to said finger members.

2. A jaw-forming machine comprising a vertically movable member carrying a punch member and forming members adapted to contact with the ends of unformed jaws a die operatively associated with said punch member and reciprocating means adapted to move under the control of said vertically movable member to feed unformed jaws from said die to said forming members.

3. A machine comprising a ram carrying a punch member, a die member operatively associated therewith, a former, former arms mounted on said ram adapted to contact with and bend blanks around said former and means for feeding blanks from said die to said former.

4. A machine for the formation of jaw members, comprising a ram, a punch on said ram and a die operatively associated with said punch, a slidable member being located

beneath said die adapted to move cut blanks from below and forwardly of said die.

5. A blank-forming machine having a die-cutting mechanism comprising a ram, and a shaping mechanism, a slidable member adapted to move the blanks from the die-cutting mechanism to the shaping mechanism, a cam on said ram and an arm attached to said slidable member and lying in the path of said cam.

10. 6. A die-cutting and blank-forming machine having a ram a cam on said ram, an arm having one end in the path of said cam, a slidable member adapted to move the blank laterally of the ram and operatively connected to said arm.

20. 7. A machine for the formation of jaw members from blanks having a ram, a cam and fixed former-arms on said ram adapted to contact with said blanks, a former adapted to operate with said former arms, a slidable member operatively associated with said cam and adapted to move the blanks on to said former.

25. 8. A machine according to claim 6 having a further slidable and relatively movable member operatively connected to said arm and adapted to eject the formed blank from the machine.

30. 9. A machine according to claim 7 having a pair of slidable members operatively associated with said cam and adapted to eject the formed blank from said former.

35. 10. A machine for forming jaw members from blanks comprising a ram, a punch, a cam and finger members on said ram, a die and a former, an arm having one end in the path of said cam and a pair of slidable members operatively connected to said arm and adapted to move the blank from the die to the former and to eject the formed blank from the former respectively.

40. 11. A die-cutting and blank forming machine comprising a ram having a punch, a die bed, a die on said die bed to cooperate with said punch, said die and die bed having slots in register, forming means adjacent said die and means for moving cut blanks from the base of the slot to said forming means.

45. 12. A die-cutting and blank forming machine according to claim 11 having clamping means on said die bed adapted to clamp the blanks subsequent to said movement.

50. 13. A die-cutting and blank forming machine comprising a ram for cutting said blanks, a former, finger members on said ram adapted to contact with said blanks and bend the same on said former, and clamping means on a fixed part of the machine adapted to clamp the blanks on said former prior to contact by said finger members.

55. 14. A die-cutting and blank forming machine comprising a ram for cutting said blanks, a former, a clamping member on a fixed part of the machine adapted to clamp

the blanks on the former, and a cam on said ram adapted to actuate said clamping member.

60. 15. A die-cutting and blank forming machine comprising a die, a ram, a punch on said ram cooperating with said die, a former, means for feeding the blanks from said die to said former and resilient supporting means for supporting said blanks on said former.

65. 16. A die-cutting and blank forming machine according to claim 15 having clamping means actuated by said ram for clamping the blanks on the former.

70. 17. A die-cutting and blank forming machine comprising a ram for cutting the blanks, a former, means for feeding the blanks to said former, finger members on said ram adapted to contact with the blanks to bend the same around the former, and resilient supporting means for said blanks adapted to be moved by said finger members.

75. 18. A die-cutting and blank forming machine comprising a ram, a punch on said ram, a die cooperating with said punch and having a slot, a former, means for moving blanks from the base of said slot to said former, finger members on said ram for bending the blanks around said former and resilient supporting means for said blanks adapted to be moved by said finger members.

80. 19. A die-cutting and blank forming machine according to claim 18 having clamping means actuated by said ram for holding the blanks on the former.

85. In testimony whereof I affix my signature.
JOSEPH D. ZAHM.
